BINDER MECHANISM

Hubert Auburn, Mount Healthy, Ohio, assignor to
The Tenacity Manufacturing Co., Lockland,
Ohio, a corporation of Ohio

Application February 3, 1938, Serial No. 188,536

2 Claims. (Cl. 129—24)

This invention relates to binders of the general character shown in my Patents 1,890,139, 1,891,037 and 2,017,934.

An object of the invention is to provide a device of that general character, provided with means for automatically connecting the posts of the binder and the latch means ordinarily provided in such devices, for attaching the posts to the back and cover members of the binder.

Another object is to provide means for effecting automatic connection of the posts and binder parts, and which do not require closing of the book or binder for attaining such automatic connection, and which means are not intended to effect automatic connection of such parts of a binder, incidental to closing of the book or binder. Thus, there is obviated the possibility of any one using a binder, being deceived into thinking that the said book parts are secured, whereas in fact, as happens frequently in practice, the parts do not function properly, for various reasons, with the result that the unsecured posts permit the contents of the book to fall from the book, with resultant confusion of the pages that detach themselves from the posts, if the posts are not secured as intended, and the book should be so handled that the weight of the contents or leaves of the binder is directed upon the unsecured posts. In other words, while it is intended to provide means for automatic connection between the posts and binder parts, yet a positive and intentional relative movement of the posts and cooperative parts is required for attaining such automatic action.

Another object is to provide means for the purposes stated, that will give an effective and substantial connection of the indicated parts, as distinguished from prior art devices intended generally to accomplish similar automatic connection of such parts, but in which the parts, after initial connection, require a further manual operation for providing an effective connection of the parts, adapted to withstand the ordinary usage to which such devices are subjected. It is therefore intended to obviate the disastrous consequences, often attendant upon use of such prior art devices, when the user thereof fails to supply the additional manual operation referred to, after the making of the first and inadequate automatic connection of the indicated parts.

Another object is to provide simple and efficient means for attaining the indicated results.

These and other objects are attained by the means described herein and disclosed in the accompanying drawing, in which:

Fig. 1 is a fragmental end elevational view, showing a binder of the character referred to, and embodying the invention.

Fig. 2 is an enlarged longitudinal sectional view of a casing showing operating parts, and forming details of the invention.

Fig. 3 is an enlarged sectional view, on line 3—3 of Fig. 2.

Fig. 4 is a sectional view on line 4—4 of Fig. 3.

As shown in the accompanying drawing, the back 10 comprises a metal plate 11, which serves as a foundation or mounting member for a pair of fixed inverted U-shaped hollow metal housings 12 and 13. The housings, their method of attachment and the parts associated and co-operating with each of them may be identical, wherefore an explanation of one such housing and its associated parts will be given.

Each of the arms 14 and 15 of the inverted U-shaped housing 12 is provided along its edge, 20 with spaced lugs 16 and 17 which are inserted in spaced complementary slots 18 and 19 and are turned over as shown in Fig. 3, for mounting the housing on the plate 11.

An elongated flat bar 21 is positioned within 25 the lower part of chamber 20 which is formed within the housing 12. The bar 21 may be termed a cam bar or an actuating bar, inasmuch as its function is to operate certain parts associated with the post holding pintles 24 and 25, 30 which in turn may engage and retain the posts 23. A shell or casing 22 comprising a bottom 51, side walls 52 and 53 and end walls 54 and 55 which terminate in outwardly extending lips 56 and 57, is positioned within the upper part of 35 chamber 20 by any suitable means such as by spot welding or by rivets 50 which may extend through lips 56 and 57 and the upper edge of housing 12.

The cam bar 21 is provided at intervals with 40 cam faces 26, shown herein as inclined faces, adapted to cooperate with a wedge 27 comprising a pin-like extension 28 extending through an aperture 29 in the bottom 51 of housing 22 45 and riding upon the cam face 26.

The wedge body 30 cooperates with inclined faces 31 and 32 formed on pintle blocks 33 and 34 respectively, and which blocks comprise the pintles 24 and 25, respectively. Springs 35 and 36, shown herein as coils or spirals, but which may be of any other type or form, operate upon the blocks 33 and 34, respectively, and yieldingly urge the blocks toward one another. The arrangement of blocks, wedge, etc., may be posi- 55

tioned in the interior of housing 22 as clearly shown in Fig. 2.

A separate shell arrangement may be provided for each post, of which there are generally four or more provided for each binder. The shell-like arrangement permits each set of pintles, springs and wedge to be fabricated as a complete unit, each of which may be introduced separately into the housing and be secured in proper position 10 within the housing. Thus assembly of the pintle blocks and their cooperating parts, as well as the assembly of such units with the housing, may be simplified and expedited. Incidentally, the housings 12 and 13 serve as supports for the 15 posts, when the various parts of the binder are assembled in their normal positions.

The pintles 24 and 25 are normally disposed at the registering openings 41 and 42 provided in the housing 12 and shell 22, respectively, and into 20 which openings the post extends for engagement with the pintles. The outwardly exposed faces 43 of the pintles are inclined so they will cooperate with the rounded edges 44 of the post for retracting the pintles, against the yielding 25 resistance of the springs. The said inclined or tapered portions of the pintles are sufficiently long that a substantial portion of each one of a pair of pintles associated with each post, will provide an adequate and substantial bearing and 30 support for the post, at both sides of the post. Thus, any canting of the post is prevented.

In the operation of the device, movement of the cam bar in one direction forces the wedge upwardly between the pintle blocks, thus separating 35 the pintles and releasing the post. If desired, a spring 45, having connection with the cam bar and housing, yieldingly retains the cam bar in its normal position. When it is desired to secure the posts by the pintles, the rounded

ends of the posts, which incidentally register with the respective openings provided therefor in the housing, are pressed against the pintles. The pintles, acting under such pressure and the yielding influence of their associated springs, 5 automatically secure the posts.

What is claimed is:

1. In a device of the class described the combination of a binder comprising a support of a width exceeding its thickness, and having notches 10 in the edge thereof, and posts for cooperation with the edge notches of the support, a pair of spaced pintle blocks located within the support, in coplanar relationship, and including pintles for each post, each pair of pintles being exposed 15 through a single edge notch for engaging their respective posts, and cooperating means associated with the posts and pintles for automatically engaging the pintles with their respective posts, incident to movement of the posts into the 20 edge notches of the support member.

2. In a device of the class described the combination of a binder comprising a support of a width exceeding its thickness, and having notches 25 in the edge thereof, and posts for cooperation with the edge notches of the support, a pair of spaced pintle blocks located within the support, in coplanar relationship, and including pintles for each post, each pair of pintles being exposed 30 through a single edge notch for engaging their respective posts, cooperating means associated with the posts and pintles for automatically engaging the pintles with their respective posts, incident to movement of the posts into the edge notches of the support member and manually 35 operable means for separating the pintles for releasing the posts.

HUBERT AUBURN.
